UNITED STATES PATENT OFFICE.

LAWRENCE R. BLACKMORE, OF ARLINGTON, NEW JERSEY, ASSIGNOR
TO THE BLACKMORE ENGINEERING COMPANY, OF ARLINGTON, NEW
JERSEY, A CORPORATION OF NEW JERSEY.

RUBBER PRINTING-STAMP.

No. 828,704.

Specification of Letters Patent.

Patented Aug. 14, 1906.

Application filed October 23, 1905. Serial No. 283,906.

To all whom it may concern:

Be it known that I, LAWRENCE R. BLACKMORE, a citizen of the United States, residing at Arlington, Essex county, State of New Jersey, have invented certain new and useful Improvements in Rubber Printing-Stamp, of which the following is a specification.

My improvements relate to the specific construction of the blank rubber strips from which flexible resilient bases for rubber types are made, as well as to the bases themselves, said bases being interposed between the types and the stamp-blocks for the purpose of affording a medium of support which will equalize and distribute pressure and insure a perfect printing contact under the varying conditions of use.

The object of my invention is to increase the sensitiveness and flexibility of each base while maintaining the requisite degree of resilience and at the same time to afford a base the whole surface of which is practically a smooth continuous non-absorbent skin of close impervious texture.

To this end the invention consists, primarily, in a blank strip of rubber formed with a series of hollow columns having intersecting grooves between them, said hollow columns being connected by very narrow thin webs forming the bottoms of said intersecting grooves and constituting convenient lines of severance, whereby a portion of the strip of suitable area and shape may be detached to form a type-base, the said lines of severance being practically coincident with the external side walls of the columns, so that there is no marginal waste of web or protrusion thereof beyond the outer circumscribing walls of the base thus formed. Incidentally the invention includes the combination with such base of a suitable stamp-block and rubber printing-types and in certain other features hereinafter described and claimed specifically.

An important feature in the manufacture of my blank rubber strip consists in forming it in a mold having intersecting partitions with sharp convergent edges which extend to the "skin" formed by the contact of the rubber with the opposed surface of the mold, as hereinafter set forth, by which means the sides of adjoining hollow columns con-

verge and meet in a sharp well-defined line of severance, so that when an incision is made through the web along one of these lines of severance the new surfaces exposed will not only form continuations of the external side walls of the columns, but will also be found to be as smooth and imperforate as said walls of the column, thus affording a continuous unbroken non-absorbent surface throughout the type-base. At the same time this skin web is of sufficient thickness and strength to hold the hollow columns together under ordinary conditions of storage, transportation, or manipulation and until forcibly severed by a sharp instrument for the purpose above set forth. Thus practically any number of the hollow columns may be detached from the strip to form a base of any desired configuration and dimensions, restricted only by the length and breadth of the strip and the size of its hollow columns without "opening up" or exposing the internal structure of the rubber. I thus attain an individual stamp base or backing of exceptional resilience, since the hollow columns constituting a series of sealed air-cells when attached to the stamp-block are sensitive and quick in adapting themselves to all variations in pressure, while at the same time the base, without trimming or special preparation, affords a continuous unbroken external skin or surface which presents a symmetrical appearance, prevents absorption of ink, dirt, or extraneous matter of any kind, and protects the internal relatively soft porous texture of the rubber against the otherwise deteriorating influences of the atmosphere.

It is to be understood that I do not restrict myself to any particular shape in cross-section of the hollow columns into which the strip is subdivided by the intersecting severing-grooves provided the connecting-webs at the bottom of the latter are of less width and thickness than the walls of said hollow columns and do not exceed in thickness that of the skin common to the whole surface of the strip. Thus instead of a series of hollow cubic columns with grooves between them the sides of which are essentially vertical the hollow columns may be of truncated pyramidal form, the resulting severing-grooves with in-

clined convergent sides meeting at a sharp angle in the web at the bottom of said grooves, thereby providing an ideal line of severance, while the width of such grooves affords ample scope for the lateral and individual expansion of the hollow columns. This freedom of individual lateral expansion of the hollow columns by reason of the intersecting severing-grooves adds materially to the flexibility and resilience of the base, enabling it, in part or in whole, to adapt itself more readily to any and all inequalities of surface to which the printing-types may be applied.

In the accompanying drawings, Figures 1 and 2 are respectively side and end views of a hand-stamp embodying the essential features of my invention. Fig. 3 is an isometrical perspective showing a blank strip formed with hollow cellular columns. Figs. 4 and 5 are respectively top and bottom views of a base severed from the strip shown in Fig. 3. Fig. 6 is a transverse section upon plane of line 6 6, Fig. 4. Fig. 7 is a transverse section upon plane of line 7 7, Fig. 6. Fig. 8 is a sectional detail illustrating the bending of the strip on one of the lines of severance. Fig. 9 shows diagrammatically a portion of a strip having columns in the form of rectangular parallelograms. Fig. 10 is a similar view showing the lines of severance crossing the strip diagonally, Fig. 11, a similar view showing columns of rhomboidal shape. Fig. 12 is an isometrical view of a portion of a strip having columns of truncated pyramidal shape; Fig. 13, a top view of the structure shown in Fig. 12. Fig. 14 is a top view of a portion of a matrix used in the manufacture of the strip shown in Figs. 3 to 8, inclusive, the parts being materially enlarged for convenience of illustration. Fig. 15 is a view showing a portion of the matrix used in the manufacture of the strip illustrated in Figs. 3 to 8, inclusive. Fig. 16 is a section upon plane of line 16 16, Fig. 15. Fig. 17 is a view showing the form of matrix used in the manufacture of the strip shown in Figs. 12, 13, and 14. Fig. 18 is a section upon plane of line 18 18, Fig. 17.

In the drawings, A represents a stamp-block of any ordinary or desired construction provided with a handle a. To the face a' of this stamp-block A is attached the flexible resilient type support or cushion or base B, which forms the essential feature of my invention.

The base B may be attached directly to the face a' of the stamp-block A or indirectly through the medium of a sheet or layer c of rubber or other suitable material interposed between the face a' of the stamp-block at any stage in the manufacture of the stamp as a whole. The rubber type T are attached, preferably, to the bottom or continuous web w of the base B, although this is not essential.

The type cushion or base B consists of a section of a blank strip S of the required size formed by cutting the connecting-web w at the bottom of the severing-groove g. These severing-grooves g are created by intersecting partitions m in the matrix M, used in manufacture of the strip S—such, for instance, as the rectangular partitions shown by way of illustration upon a greatly-enlarged scale in Figs. 15 to 18, inclusive, by reference to which it will be seen that the edges of the partitions are preferably sharp or convergent, so as to form very narrow bottoms to the grooves g, thus creating very thin well-defined lines for the severance of the web w of the blank strip. In fact, this narrowing of the bottom of each severing-groove g to a sharp thin line meeting or extending into the skin formed by the contact of the rubber with the inner surfaces of the mold is an important factor in the construction of the blank strip S, since I thereby attain a line of severance which leaves no margin or selvage and which does not open up or expose the internal structure of the strip S or of the type-base B made therefrom. By preference the partitions, even for the forms of strip shown in the first eleven views of the drawings, are made convergent or knife-shaped in cross-section, so that the difference between the partitions shown in Figs. 15 and 16, as compared with those shown in Figs. 17 and 18, is essentially only one of breadth of base, although the columns d, formed on the strip S by the partitions m, are in the first instance mentioned practically square and uniform in dimensions, while in the latter instance they are in the form of truncated pyramids. In either case I attain my object in the creation of a tough but thin narrow ligature or well-defined line of severance at the bottom of the groove g and between the opposed sides thereof that will result in clean compact air-tight and non-absorbent edges on either side of the cut. The grooves g, to a greater or less extent in proportion to the degree of convergence or space between their opposed side walls, also perform another important function in that they afford scope for individual lateral expansion by and between the columns d, which is important because it increases and renders more uniform and responsive the flexibility of the type-base B, so that the inner or central portion thereof will yield as readily as the marginal portions, and thus allow the rubber types to adapt themselves more readily to inequalities of surface or pressure. Furthermore, this provision for the lateral expansion of the columns d obviates very largely any danger of cellular rupture under undue pressure.

In order to attain a relatively high degree of elasticity and resilience, I mold cells d' within the columns d, said cells d' being

closed and hermetically sealed by the face a' of the stamp-block A or by the facing c of rubber or other soft elastic material interposed between the face a' of said block A and the base B, as the case may be.

Obviously the intersecting lines of severance g between the hollow columns d are arranged to the best advantage when extended longitudinally and transversely of the strip S and at right angles to each other, as waste of material is thus avoided, since the elastic type cushions or bases B usually required are of elongated rectangular form. At the same time other arrangements of the intersecting lines of severance g may be resorted to without departing from the spirit and intent of my invention by which I afford a blank strip S, from which practically a type-base B of any desired length and width may be quickly and conveniently cut, said base being then ready for immediate application and use and being complete and perfect in all its parts, with a continuous hermetically-sealed surface and with no protuberances or roughness of surface. Hence the internal structure is effectually protected against the deteriorating effects of the atmosphere, there can be no absorption or contamination, and a smooth external surface is afforded which can readily be kept clean.

What I claim as my invention, and desire to secure by Letters Patent, is—

1. In a hand-stamp, the combination with the stamp-block of a rubber type-base attached thereto consisting of an integral strip of rubber formed with intersecting grooves with hollow columns between them, said hollow columns being united at the bottom of the said intersecting grooves by thin narrow webs of less width than the thickness of the side walls of said hollow columns, said webs consisting of the "skin" at the bottom of said intersecting grooves, and all the surfaces of the blank being formed with a smooth continuous surface, together with a rubber type-plate attached to the rubber type-base.

2. In a hand-stamp, the combination with the stamp-block of a rubber type-base attached thereto consisting of an integral strip of rubber formed with intersecting grooves with hollow columns between them, said hollow columns being united by a web consisting of the "skin" at the bottom of the said intersecting grooves, the sides of which latter extend down to said "skin" where they intersect each other, so as to form sharp and well-defined lines of severance for the purpose described, together with a rubber type-plate attached to the said rubber type-base.

3. As an article of manufacture, a hand-stamp consisting of a rubber type-plate mounted upon a hollow flexible rubber cush-

ion formed with a series of adjoining cells having independent side walls the opposed 65 sides of said adjoining cells being united by thin narrow webs consisting of the "skin" at the base of the cells, said webs being of less width than the thickness of the cell-walls and the edges of said walls being attached to the 70 stamp-block, together with said stamp-block, for the purpose described.

4. A base-plate for hand-stamps consisting of an integral strip of rubber formed with parallel series of independent hollow columns 75 united by webs or ligatures of less width than the thickness of the walls of the hollow columns, for the purpose described.

5. A base-plate for hand-stamps consisting of an integral strip of rubber formed with 80 parallel series of independent hollow columns which are quadrangular in cross-section united by webs or ligatures of less width than the thickness of the walls of said hollow columns, for the purpose described.

6. A molded blank for rubber type-bases consisting of an integral strip of rubber formed with two series of parallel severing-grooves, one series intersecting the other, with hollow columns united by thin narrow 90 webs of less width than the thickness of the walls of the columns, said webs consisting of the "skin" at the bottoms of said intersecting grooves.

7. A molded blank for rubber type-bases 95 consisting of an integral strip of rubber formed with two series of parallel severing-grooves intersecting each other at right angles, with hollow quadrangular columns united by thin narrow webs of less width than 100 the thickness of the walls of said hollow quadrangular columns, said webs consisting of the "skin" at the bottom of said intersecting grooves.

8. A molded blank for rubber type-bases 105 consisting of an integral strip of rubber formed with a series of longitudinal parallel severing-grooves and a series of transverse parallel severing-grooves, with square hollow columns between them united by thin narrow webs of less width than the thickness of the walls of said square hollow columns, said webs consisting of the "skin" at the bottom of said intersecting grooves.

9. A molded blank for rubber type-bases 115 consisting of an integral strip of rubber formed with two series of parallel severing-grooves, one series intersecting the other, with hollow columns between them united by webs consisting of the "skin" at the bottoms 120 of said intersecting grooves the sides of which extend down to said "skin" where they intersect each other to form sharp well-defined lines of severance, for the purpose described.

10. A molded blank for rubber type-bases 125

consisting of an integral strip of rubber formed with two series of parallel grooves, one series intersecting the other, with columns between them united by webs consisting of the "skin" at the bottoms of said intersecting grooves the sides of which latter extend down to the said "skin" and inter-

sect it and each other to form sharp well-defined lines of severance for the purpose described.
